Fig. 1.

UNITED STATES PATENT OFFICE.

CHARLES G. ETTE, OF ST. LOUIS, MISSOURI, ASSIGNOR TO ETTE INVESTMENT COMPANY, OF ST. LOUIS, MISSOURI, A CORPORATION OF MISSOURI.

POLE CROSS-ARM.

1,027,711.

specification of Letters Patent. Patented May 28, 1912.

Application filed November 22, 1911. Serial No. 661,769.

To all whom it may concern:

Be it known that I, CHARLES G. ETTE, a citizen of the United States, residing at St. Louis, Missouri, have invented a certain new and useful Improvement in Pole Cross-Arms, of which the following is a full, clear, and exact description, such as will enable others skilled in the art to which it appertains to make and use the same.

10 This invention relates to cross-arms such as are used on poles for carrying insulators.

The main object of the invention is to provide a metallic insulator-supporting structure that can be manufactured at a lower 15 cost than the wooden cross-arms now in general use and which is more efficient, lighter, and has a greater capacity than a wooden insulator-supporting structure. And another object of my invention is to provide 20 a metallic insulator-supporting structure in which the insulator-pins can be applied or removed easily, and which is so designed that the pins cannot work loose from the insulators or from the member which supports 25 the insulator-pins.

Other objects and desirable features of my invention will be hereinafter pointed out.

Briefly stated, my invention consists in an 30 insulator-supporting structure that comprises a metallic cross-arm member having laterally projecting flanges that are tapered or provided with faces which are inclined with relation to the insulator-pins, and vertically disposed insulator-pins that pass 35 through openings in said flanges and which are formed from iron rods provided with screw-threaded portions for receiving nuts which bear upon the inclined faces on the flanges of said cross-arm member.

40 Figure 1 of the drawings is a front elevational view of a metallic insulator-supporting structure constructed in accordance with my invention; Fig. 2 is a similar view showing how the lower insulator-pins can 45 be arranged so that the insulators mounted thereon will lie directly under the insulators on the upper pins; Fig. 3 is a transverse sectional view of the cross-arm member showing how the tapered flanges thereon 50 prevent the nuts on the insulator-pins from turning; Fig. 4 is an end view of the cross arm member showing one kind of nut that can be used with the insulator-pins; Fig. 5 is an end view showing one way of preventing 55 the insulator-pins from moving vertically

60 cally relatively to the cross-arm member; and Fig. 6 is an end view showing the insulator-pins arranged in such a position with relation to the vertical web of the cross-arm member that said web prevents the nuts on 60 the pins from turning.

Referring to the drawings which illustrate my invention, A designates a metallic cross-arm member which consists of a vertically disposed web provided with a pair of laterally projecting flanges 1 whose inner faces 2 are inclined with relation to the vertical web, the outer faces of said flanges 1 lying at approximately right angles to the vertical web of the member A, thus forming a channel-shaped member whose horizontal legs or flanges are tapered. The member A is provided with a plurality of metallic insulator-pins that pass through both flanges 1 of the member A and which are locked in position 75 by means of nuts that coöperate with the flanges 1 on said cross-arm member. In the embodiment of my invention herein shown, a set of insulator-pins B are arranged on the upper side of the cross-arm member A, 80 and a set of insulator-pins C are arranged on the lower side of said member, the lower insulator-pins C being preferably designed in such a manner that they can be adjusted so as to arrange the insulators 85 thereon in staggered relation to the insulators on the upper pins or directly underneath the insulators on the upper pins, thereby enabling a large number of insulator-pins 90 to be mounted on a comparatively short cross-arm. Both sets of pins are preferably formed from iron rods which have been cut into short lengths or sections and threaded at one end to receive the heads D on which the insulators are screwed, and threaded at 95 their opposite ends to receive the nuts which coöperate with the tapered flanges on the member A to hold the pins in position and prevent them from turning relatively to the member A. The upper insulator-pins B pass 100 vertically through alining holes or openings in the flanges 1 on the member A, and nuts 3 and 4 are arranged on the screw-threaded portions 5 at the lower ends of said pins above and below the bottom flange 1 of the cross-arm member A so as to lock the pins 105 in position and prevent them from turning. The upper pins B are arranged in position by inserting them in the openings in the top flange of the member A, then screwing the nuts 110

- 3 onto the screw-threaded portions of said pins, and finally inserting the pins through the bottom flange of the member A and screwing the nuts 4 onto the screw-threaded portions 5 of the pins on the under side of the bottom flange of the member A. In view of the fact that the surface of the member A, against which the nuts 3 bear, is inclined with relation to the pins B, it will be impossible for the pins B and nuts 3 to turn or rotate relatively to the member A, even if the nuts 4 on the under side of the bottom flange of the member A are not screwed up tightly against said flange for any movement of the nuts 3 causes them to cant and thus grip the pins tightly. Consequently, the vibration of the wires which are connected to the insulators has no effect on the insulator-pins and will not cause the heads D of the pins to screw out of the insulators because the nuts 3 and the coöperating inclined surface on the bottom flange of the member A on which said nuts bear, positively prevents the insulator-pins from turning. Nor is it possible for the pins to turn or rotate in the nuts 3 for said nuts bear upon the inclined face of the bottom flange of the member A and thus prevent the pins from turning in one direction, and the wires which are connected to the insulators that are mounted on the heads on the pins B prevent the pins from turning in the opposite direction, it being, of course, understood that the insulators are screwed down tight upon the heads D of the upper pins.
- While I have stated that nuts 4 are screwed onto the lower ends of the pins B underneath the bottom flange of the cross-arm member A so as to prevent the pins from moving upwardly, the nuts 4 could be omitted and the lower ends of the pins could be bent laterally, as shown in Fig. 5, so as to prevent them from moving upwardly. Ordinary nuts, either square or hexagonal-shape, can be used with the pins, or, if desired, nuts 13 which are tapered or inclined on the under side could be mounted on the pins above the bottom flange of the member A, as shown in Fig. 4.
- The lower pins C, which are arranged on the under side of the cross-arm member A, pass upwardly through holes in the horizontal flanges of said member, and nuts 3^a and 4^a are mounted on the screw-threaded portion 5^a at the upper ends of said pins and are arranged on opposite sides of the top flange of the member A so as to prevent the pins C from turning or moving vertically. The lower pins C are provided with laterally projecting upturned arms 6 on which insulator-heads D' are mounted so as to permit the insulators on the under

side of the cross-arm member A to be arranged either in staggered relation to the insulators on the upper side of the cross-arm member A, as shown in Fig. 1, or directly underneath the upper insulator-pins B, as shown in Fig. 2.

Instead of relying upon the inclined inner faces of the flanges 1 on the cross-arm member A to prevent the nuts 3 and 3^a from turning, the openings in the flanges on the member A, through which the insulator-pins pass, can be formed close enough to the vertical web of said member to cause said nuts to strike against said vertical web in case the nuts start to turn, this feature being illustrated in Fig. 6.

While I have herein shown only one means for preventing the lower pins C from moving downwardly, namely, the nuts 4^a which are arranged above the top flange of the cross-arm member A, it will, of course, be understood that said nuts could be omitted and the upper ends of the pins bent over or turned laterally in the same manner illustrated in Fig. 5.

Having thus described my invention, what I claim as new and desire to secure by Letters Patent is:

1. A cross-arm member provided with laterally projecting flanges that have inclined surfaces, a vertically disposed insulator-pin passing through said flanges, a nut mounted on said pin and bearing upon the inclined face of one of said flanges, and means located on the other side of said flange for preventing the pin from moving vertically in one direction.

2. A cross-arm member provided with laterally projecting flanges that have inclined faces, an insulator-pin passing through said flanges and provided with a screw-threaded portion, and nuts mounted on said screw-threaded portion and arranged on opposite sides of one of said flanges, one of said nuts being adapted to bear upon the inclined face on said flange.

3. A cross-arm consisting of a substantially channel-shaped member provided with laterally projecting flanges whose inner faces are inclined, a vertically disposed insulator-pin passing through both of said flanges, and a nut arranged on said pin and provided with an inclined face that bears against the inclined face on one of said flanges.

In testimony whereof I hereunto affix my signature in the presence of two witnesses, this twentieth day of November 1911.

CHARLES G. ETTE.
